UNITED STATES PATENT OFFICE.

ARTHUR H. S. WARD, OF LONDON, ENGLAND.

DESIGN FOR A CORK OR STOPPER FOR BOTTLES.

54,294.

Specification for Design.

Patented Dec. 9, 1919.

Application filed July 23, 1919. Serial No. 312,840. Term of patent 14 years.

To all whom it may concern:

Be it known that I, ARTHUR HENRY SARSFIELD WARD, a subject of the King of Great Britain, residing at London, England, have invented a new, original, and ornamental Design for a Cork or Stopper for Bottles, of which the following is a specification, reference being made to the accompanying drawing, forming part thereof.

The figure is an elevation of the cork or stopper for bottles, as shown.

I claim.

The ornamental design for a cork or stopper for bottles, as shown.

ARTHUR H. S. WARD.
